UNITED STATES PATENT OFFICE

CHARLES R. KILLINGBECK, OF TROY, NEW YORK.

LOCOMOTIVE-VALVE.

SPECIFICATION forming part of Letters Patent No. 453,400, dated June 2, 1891.

Application filed November 26, 1890. Serial No. 372,618. (No model.)

To all whom it may concern:

Be it known that I, CHARLES R. KILLINGBECK, of the city of Troy, county of Rensselaer, and State of New York, have invented a new and useful Improvement in Locomotive Steam-Cylinder Valves, of which the following is a specification.

My invention relates to improvements in locomotive steam-cylinder valves to adapt them to supply exhaust-steam for heating purposes by constructing the exhaust-port of the valve so that a portion of the exhaust-steam will pass to the smoke-stack in the usual way, and another portion of it will be directed into a pipe by which it is conducted to and through the cars, said pipe being preferably passed through one of the boiler-flues to the cab, whereat it is provided with a valve where the pressure and measure of steam to be utilized for heating purposes may be regulated.

Accompanying this specification to form a part of it there are two plates of drawings, containing four figures, illustrating my invention, with the same designation of parts by letter reference used in all of them.

Of the illustrations, Figure 1 shows my invention as applied to a locomotive, with the pipe that conveys the exhaust-steam (that is used for heating) through a boiler-flue to the cab, indicated by a dotted line. Fig. 2 is a cross-section taken centrally through one of the steam-cylinders of a locomotive, also through the steam-chest, through the valve-seat and valve and a cross-partition arranged in that part of the exhaust-port which is in the slide-valve and a partition that is also arranged in that part of the exhaust-port which is in the valve-seat. This figure also illustrates in section the pipe which connects with the exhaust-port and conveys a part of the exhaust-steam to the smoke-stack and shows also the pipe which conveys away part of the exhaust-steam for heating purposes, with part of the latter pipe shown in section. Fig. 3 is a longitudinal central section taken through one of the steam-cylinders of a locomotive, the steam-chest upon said cylinder, the slide-valve, the valve-seat, with the piston and valve-rod shown in elevation. Fig. 4 is a perspective of the slide-valve of a locomotive steam-cylinder with what is its under-

side when in place, (shown as turned uppermost in the illustration,) and illustrating a partition arranged in that part of the exhaust-port which is made in the under side of the slide-valve to divide such portion of the exhaust-port in two parts. 55

The several parts of the apparatus thus illustrated are designated by letter reference, 60 and the function of the parts is described as follows: The letter C designates the steam-cylinder; S, the steam-chest; P, the steam-cylinder piston; R, the piston-rod; B, the boiler; S², the smoke-stack; C², the cab; T, the tender, and E E the steam-ports.

The letter V' designates the slide-valve, and v² its operating-rod; A', that part of the exhaust-port that is formed in the slide-valve. 70

The letters E E designate the steam-ports leading from the steam-chest to the steam-cylinder, over which ports the slide-valve V' is reciprocatingly moved on the valve-seat V².

The letter W' designates a partition that is 75 arranged in that part of the exhaust-port A' made in the under side of the slide-valve, and this partition is arranged to be parallel to the line of direction in which the slide-valve is operated by the rod v². This partition W' 80 divides that portion of the exhaust-port formed in the under side of the slide-valve V', and indicated at A' into two parts a' and a².

The letter W² designates a partition that is 85 arranged within that part of the exhaust-port which is formed in the valve-seat V² and indicated at A², Fig. 2, and this partition W² divides said exhaust-port part A² in two inclosures b' and b², with said partition W² arranged to be vertically in line with the partition part W', formed in the slide-valve V', before described. As thus made and arranged the exhaust-port is divided in two parts B' B² by the partitions W' and W², so 90 that as the slide-valve moves over the face of the valve-seat, these partitions being vertically in line, and that one of the latter arranged in the slide-valve being parallel to the movement of the latter, there is a constant 95 division of the exhaust-steam, one portion passing from the part a' of the exhaust-port of the slide-valve into the part b' of the valve-seat, said two parts of the exhaust-port 100

forming the chamber B', and the other part of the exhaust-steam passes through the exhaust-port part a² of the slide-valve into the exhaust-port part b² of the valve-seat, said 5 two parts of the exhaust-port producing the chamber B².

The letters p' designate a pipe leading from the exhaust-port part B' to the smoke-stack of the locomotive, and the letter p² designates another pipe leading from the exhaust-port part B² to pass through one of the boiler-flues to the cab, and from thence by connection with the passenger-coaches. (Not shown.)

15 The letter K designates a check-valve arranged on the pipe p², and V⁴ a valve on the said pipe arranged within the cab.

Preferably the exhaust-port part B² is made to take steam a little sooner than the exhaust-port part B', and for this purpose the exhaust-port part a', formed in the under side of the slide-valve, is given a little lead, as shown at l, Fig. 4, by being made a little longer than that part of the exhaust-port indicated 25 at B'. The chamber B' is preferably made smaller in area than the chamber B². As thus made and arranged a part of the exhaust-steam is available for heating purposes, with the measure of it necessary for 30 that purpose regulated by the engineer in charge of the locomotive.

While I have shown my invention as applied to a locomotive steam-cylinder to utilize a part of the exhaust-steam for heating purposes, my invention may be applied to any steam-cylinder having an equivalent arrangement of steam-chest, sliding valve, valve-seat, and exhaust-port for like uses.

Having thus described my invention, what 40 I claim, and desire to secure by Letters Patent, is—

1. The combination, with a steam-cylinder having a piston and provided with a valve-seat having steam-entry ports leading to said 45 cylinder and an exhaust-port leading therefrom, of a two-part partition dividing the exhaust-port in two parts, and a pipe connected with each of the divided-off exhaust-port parts to conduct steam therefrom, substantially in the manner as and for the purposes set forth.

2. The combination, with a steam-cylinder having a piston and a sliding valve provided with an exhaust-port part formed in its lower 55 face and constructed with a valve-seat having entry-ports leading to the steam-cylinder

and an exhaust-port part leading therefrom, of a partition arranged in the exhaust-port part of the sliding valve, a partition arranged in the exhaust-port part of the valve-seat, 60 said partition being in line with the partition in the slide-valve exhaust-port part, and a pipe connecting with each of the divided-off parts of the exhaust-port, substantially in the manner as and for the purposes set forth. 65

3. The combination, with a locomotive steam-cylinder that has a piston and is provided with a sliding valve constructed with an exhaust-port part formed in its under face and provided with a valve-seat having 70 entry-ports connecting with said cylinder, and an exhaust-port part which in connection with the exhaust-port part formed in the slide-valve conducts exhaust-steam from said cylinder, of a partition dividing the area of 75 the exhaust-port part of the slide-valve in two parts, a partition arranged on the valve-seat exhaust-port part to be in line with the partition in the slide-valve exhaust-port pipe, a pipe connecting with one of the divided-off 80 areas of the exhaust-port, and a pipe connected with the other divided-off area of the exhaust-port and provided with a valve, substantially in the manner as and for the purposes set forth. 85

4. The combination, with a steam-cylinder having a piston and provided with a valve-seat having steam-entry ports leading to said cylinder and an exhaust-port leading therefrom, of a two-part partition dividing said 90 exhaust-port in two parts, with one of said exhaust-port parts constructed to take steam in advance of the other, and a pipe connecting with each of said exhaust-port parts to convey steam therefrom, substantially in the 95 manner as and for the purposes set forth.

5. The combination, with a steam-cylinder having a piston and provided with a valve-seat constructed with steam-entry ports leading to said cylinder, of an exhaust-port leading therefrom, with said exhaust-port divided in two parts, and a conduit-pipe leading from each of said divided exhaust-port parts, substantially in the manner as and for the purposes set forth. 100 105

Signed at Troy, New York, this 18th day of August, 1890, and in the presence of the two witnesses whose names are hereto written.

CHARLES R. KILLINGBECK.
